UNITED STATES PATENT OFFICE.

EDWIN R. STORM, OF NEW YORK, N. Y.

FIREPROOF FLOOR.

1,190,206.

Specification of Letters Patent.

Patented July 4, 1916.

Application filed February 23, 1911. Serial No. 610,360.

To all whom it may concern:

Be it known that I, EDWIN R. STORM, a citizen of the United States, residing at New York, in the county of New York and State of New York, have invented a new and useful Fireproof Floor, of which the following is a specification.

My invention relates to improvements in fireproof floor construction in which steel and concrete are used; and the objects of my improvement are, first, to provide a fireproof form that will receive the concrete and constitute a permanent portion of the floor; second, to provide for the concrete a fireproof form that may be placed in position with little or no false work; third, to provide a fireproof protection to the concrete; fourth, to provide a reinforcement for both the form and the concrete; fifth, to provide a fireproof protection of concrete and the form completely incasing the steel used in the floor construction; and, sixth, to provide a means for forming a flat or a paneled ceiling. I attain these objects by the devices illustrated in the accompanying drawings in which—

Figure 1 represents a section of a typical floor showing the fireproof form and its steel reinforcement used in connection with steel beams. The concrete is also shown in place with its reinforcement. Fig. 2 is a plan view of the floor construction indicated in Fig. 1, and shows the beams, the blocks composing the fireproof form in place, the reinforcement and the concrete. Fig. 3 represents a section of a typical floor showing the fireproof form and its steel reinforcement used in connection with the steel reinforcement of a concrete beam. The concrete is also shown in place with its reinforcement. Fig. 4 is a sectional view of the reinforcement for the form, showing the hooked ends and the method of roughening the surface. Fig. 5 is an isometrical view of the stirrup placed on the end of the reinforcement. Fig. 6 is a face view of the blank before being bent into the stirrup form. Fig. 7 is an isometrical projection of one of the skew-back blocks showing the back or face toward the beam. Fig. 8 is an isometrical projection of one of the skew-back blocks showing the front or face toward the key. Fig. 9 is an isometrical projection of the key or filling-piece between the two skew-backs. Fig. 10 is a sectional view of a fireproof floor showing the fireproof form molded so as to

produce a paneled effect to the ceiling formed by the under side of the floor when it is completed and the ceiling plastered. Fig. 11 represents a section of a floor showing a modification of the fireproof form adapted for moderate spans. The concrete is also shown in place with its reinforcement. Fig. 12 is an isometrical view of the fireproof form shown in Fig. 11. Fig. 13 is an isometrical view of a cover-plate.

Similar letters refer to similar parts throughout the several views.

The skew-back block A is preferably formed with walls a, b, c and d, so joined that when the block A is in position in the floor, the wall a will form a portion of the mold for the side of the concrete protection to a floor beam, or a portion of the mold for the side of a concrete beam; the wall b will form a portion of the mold for the bottom of the concrete protection to a floor beam or a portion of the mold for the bottom of a concrete beam; the wall c will form a portion of the mold for the bottom of the concrete floor arch; and the walls d will furnish support for the walls a, b and c, and also support the weight of the concrete before it sets. See Figs. 1 and 2.

The walls d are formed with the indents e of a suitable shape to fit over the steel, whether it be a beam or reinforcement. See Figs. 1, 3 and 7.

The front f, or face toward the key is formed so that the upper arris, or edge, of c is nearer the back of the block than the lower arris, or edge, of b. The surface f which will be formed of one end of each of the walls b, c and d will, in the preferred form, lie in a plane. See Figs. 1, 2, 3, 7 and 8.

The key, or filling-piece, B, between the two skew-back blocks A and A', Figs. 1, 2 and 3, is formed with a wall or web g, a bottom wall, or flange, h, and a top wall, or flange, i, and has its end l formed to fit the faces f and f' of the blocks A and A'. See Figs. 1, 2, 3 and 9.

The stirrup C is preferably formed with fingers m adapted to fit against the under-surface of the wall c; the portion n, to which the fingers m are attached, adapted to fit against the end f of the wall c; and the portion o, extending above the wall c. In the portion o is formed the hole p which may be of any desired shape and size and is adapted to receive the end q of the reinforcement D. See Figs. 1, 2, 3, 5 and 6.

The reinforcement D is formed of any suitable size and shape, preferably, with its surface roughened, the preferred form being indicated in Fig. 4 which shows portions 1 of the metal depressed below the general surface on one side and raised, as 2, the corresponding distance on the opposite side. The advantage of this form of roughening being to obtain the roughened surface without decreasing the tensile strength of the reinforcement or adding extra material to produce the roughened portions. In some of the drawings the convex or raised portions 2 are shown on the upper side but in practice they would probably be on the lower side and the cavities 1 on the upper side as in Fig. 10. One end, q, of the reinforcement D is bent to form a hook adapted to pass through the hole p and hold the stirrup C, the other end r is formed to hook over the flange u of the floor beam I. See Figs. 1, 2 and 4.

In constructing the floor when steel beams are used place the skew-back block A with its back toward the beam I and the surface t of the indents e bearing on the upper surface of the flange s; then, supporting the front end by one hand, place a stirrup C in position with a finger m, m on each side of the middle wall d and bearing against the under surface of the wall c, and the portion n bearing against the face j. Next pass the hook q of the reinforcement D through the hole p and rotating the block A on the arris or edge between t and v as far as necessary, hook the end r of the reinforcement D over the flange u of the floor beam I, allowing the block A to rotate back until it is supported at the front by the reinforcement D and at the back by the surfaces t of the walls d resting on the flange s. The block being thus rigidly supported by the beam I. See Figs. 1, 2, 7 and 8. Likewise, place the skew-back block A' with its back toward the beam I' and the surface t' of the indents e' bearing on the upper surface of the flange s'; then supporting the front end by hand, place the stirrup C' in position with a finger m' on each side of the middle wall d' and bearing against the under surface of the wall c' and the portion u' bearing against the face f'. Next pass the hook q' of the reinforcement D', through the hole p', and, rotating the block A' on the arris between t' and v' as far as necessary, hook the end r' of the reinforcement D' over the flange u' of the floor beam I', allowing the block A' to rotate back until it is supported at the front by the reinforcement D' and at the back by the surfaces t' of the walls d' resting on the flange s'. See Figs. 1 and 2. Next place the key, or filling piece, B in the space between the two skew-back blocks A and A' in such a position that the wall g will be a

continuation of the walls d and d', as indicated in Fig. 2, and the surfaces l and l' bear against the surfaces f and f'. See Figs. 1, 2 and 3.

By repeating the above process until the spaces between all the beams throughout their lengths have been filled, there will have been constructed a form for the concrete which is not only self-sustaining but which becomes a permanent part of the floor construction, saving the cost of erecting and tearing down forms. Also, where the blocks A, B and A' are made of fireproof materials, the form becomes a part of the protection to the steel-work.

By filling the space above the wall b, between the beam and the wall a, and above the wall c with concrete F, burying the reinforcement w according to the present practice, there will have been constructed a thoroughly fireproof floor having the steel protected by the concrete and the concrete in turn protected by a fire-proof material; or, if the blocks are formed of burnt clay, by a material that has been through fire; viz., withstood a higher heat in burning than would probably be generated in an ordinary conflagration. See Figs. 1 and 2.

The reinforcement D not only serves to hold the blocks A and A' before the key B is in position and to increase the carrying capacity of the form after the key is in position but it also serves as a reinforcement for the concrete arch, taking the shear at the haunches, thus producing a stronger arch with the same amount of metal, than where the metal is all placed in the reinforcement w.

The walls b and h serve as a surface to receive the plastering M for the ceiling. See Fig. 1.

In Fig. 3 is indicated a fireproof floor in which the blocks A, B and A' have been used to form the mold for a reinforced concrete beam and floor. The reinforcement for the beam being rods indicated in section by x, x. The same reinforcement D as is shown in Fig. 1 may be used or it may be modified by forming the two reinforcements of a single piece of steel as is indicated by D².

Where it is desired to produce paneled effects the portion of the wall b in front of a that is to form a part of the panel and the wall h may be raised any desired distance. If necessary, until they coincide with c and i. The walls d and g above them being raised also, as indicated in Fig. 10, where b and h are shown raised until they coincide with c and i.

While the skew-back block A has been indicated in the drawings with three carrying walls d, it may in practice have any number, as one, two, three, or more. If formed with one wall d it would be formed similarly to an end of A² shown in Fig. 12. That is, it would have an I section corre-

sponding to the section of B, Fig. 9. The wall *a* would connect the walls *b* and *c* and be of the same width as *b* and *c*, and the wall *d* would project beyond *a*, as in Fig. 12, and be formed with an indent *e* and bearing surface *t* as in Fig. 7. The front end *f* being formed to fit against the surface *l* of the key B.

In Fig. 11 is shown a modification of the mold for use where the span between the beams is not too great. This in effect, forms the blocks A, B and A' in one piece A³ having the walls *a*³, *b*³, *c*³ and *d*³. The ends of the walls *d*³ being cut away to form the bearing surfaces *t*³. If desired, the portion of *b*³ extending under the lower flange of the beam I³ may be omitted and a cover-plate Y used, having the rabbets *y* formed to fit the rabbets Z. See Figs. 11, 12 and 13. While the wall *d*³ may be formed as in Figs. 1 and 3 it may be extended any distance above the wall *c*³ and the portion above be undercut or dovetail in section, as indicated in Fig. 12. This block when in place would present the cover-plate Y, the adjacent portions of the walls *b*³, the walls *a*³, and the walls *c*³, as the retaining walls for the concrete filling F³; while the underside of the cover-plate *y* and of the walls *b*³, would constitute the surface to receive the plaster M³ for the ceiling. See Fig. 11.

The block A³ is shown with its ends provided with teeth 3, see Figs. 11 and 12. The teeth 3 serve to form additional bearing surface after the concrete has hardened. It is not necessary that the additional bearing surface take the form indicated as any projection would form a bearing.

As the essentially new element of my improved construction is a form or mold to remain permanently in place and be filled with concrete, it will be seen that the shape of the form or blocks, must vary to meet the conditions of the floor system of which it is a component. I do not, therefore, wish to be understood as confining myself to the forms indicated.

Having described my invention, I claim and desire to secure by Letters Patent:—

50 **Claims—**

1. In a concrete floor system, a bearing beam; arch-blocks having vertical sustaining walls perpendicular to, and adapted to engage with the bearing beam; and retaining walls between the sustaining walls adapted to form a mold for the concrete that is to surround the tension portion of the beam.

2. In a concrete floor system, a bearing beam; arch-blocks having vertical sustaining walls perpendicular to, and adapted to engage with, the bearing beam; retaining walls between the sustaining walls adapted to form a mold for the concrete at the bottom of the beam; retaining walls between

the sustaining walls adapted to form a mold for the floor; a concrete filling on the retaining walls for the beam and the floor; and a reinforcing rod connected to the beam and to the forward end of the arch-block, 70 and adapted to unite with and strengthen the concrete.

3. In a floor system having a concrete filling, a series of bearing beams; arch-blocks having vertical sustaining walls perpendicular to, and adapted to engage one end with a bearing beam; retaining walls between the sustaining walls adapted to form a mold for the concrete surrounding the tension portion of the beam; retaining walls between the sustaining walls adapted to become part of a mold for the concrete forming the floor; reinforcing rods connected to the beams and to the forward end of each block, and adapted to unite with and strengthen the concrete; filling-pieces having sustaining walls adapted to bear against the sustaining walls of the said arch-block; and retaining walls between the sustaining walls of the said filling-pieces adapted to 90 complete the mold for the concrete filling forming the floor.

4. In a fireproof floor construction having a concrete filling, a bearing beam; arch-blocks having vertical sustaining walls perpendicular to and adapted to engage with the bearing beam; retaining walls between the sustaining walls adapted to form a mold for the concrete surrounding the tension portion of the beam; a member adapted to 100 fit against and engage with the forward end of an arch-block; and a reinforcing rod connected to the member and to the beam.

5. Arch-blocks, for a fireproof construction having concrete filling and beams, consisting of vertical sustaining walls having notched ends; bottom walls between and formed integrally with the sustaining walls, portions of which are adapted to form part 110 of a mold for the concrete surrounding the tension portion of the beam; vertical retaining walls between and formed integrally with the sustaining walls adapted to act in conjunction with the said bottom walls to 115 form part of a mold for the concrete surrounding the tension portion of the beam; and top walls between and formed integrally with the sustaining walls, adapted to form part of a mold for the concrete at the 120 top of and between the beams.

6. In a concrete floor system having a concrete filling; members of a bearing beam; arch-blocks formed with vertical sustaining walls having one end adapted to receive the 125 members of a bearing beam; reinforcing rods sustaining the forward end of each of the said arch-blocks and adapted to unite with and strengthen the concrete; retaining walls between the sustaining walls adapted

7. To form a mold for the concrete surrounding the tension portion of the beam; and retaining walls between the sustaining walls adapted to form a mold for the concrete forming the floor.
7. In a concrete floor system having a concrete filling; tension members of a bearing beam; arch-blocks with vertical sustaining walls having one end formed to receive the tension members of a bearing beam, and the other end formed to receive a filling block; retaining walls between the sustaining walls adapted to form a mold for the concrete surrounding the tension members of the beam; retaining walls between the sustaining walls adapted to form a part of a mold for the concrete forming the floor; members adapted to fit against and engage with the forward ends of the arch-blocks; reinforcing rods connected to the said members, sustaining the forward ends of the arch-blocks; and adapted to unite with and strengthen the concrete; filling blocks with vertical sustaining walls adapted to fit against the sustaining walls of the arch-blocks; and retaining walls between the sustaining walls of the filling blocks adapted to act in conjunction with the retaining walls of the arch-blocks to form a mold for the concrete forming the floor.
8. In a concrete floor system, reinforcing members of a bearing beam; arch-blocks forming a unitary part of the said bearing beam; vertical sustaining walls in the said
- arch-blocks; retaining walls connecting the sustaining walls, and adapted to form part of a mold for the concrete surrounding and forming part of the bearing beam; a filling block having sustaining walls adapted to register with and bear against the forward ends of the sustaining walls of the arch-blocks; retaining walls connecting the sustaining walls of the filling blocks, and adapted to act in conjunction with the retaining walls of the arch-blocks to form a mold for the concrete of the floor; and a filling upon the said retaining walls.
9. In a concrete floor system, reinforcing members of a bearing beam; arch-blocks forming a unitary part of said bearing beam; vertical sustaining walls in the said arch-blocks; retaining walls connecting the sustaining walls, forming part of the mold for the concrete surrounding the reinforcing members, and part of the fire-proofing of the bearing beam; reinforcing-rods adapted to connect with and sustain the forward ends of the said arch-blocks; a filling block having sustaining walls adapted to bear against the forward ends of the sustaining walls of the arch-blocks; retaining walls connecting the sustaining walls of the filling blocks; and a filling upon the said retaining walls.
